UNITED STATES PATENT OFFICE.

MARVIN SMITHEY, OF LAWRENCEVILLE, VIRGINIA.

METER.

Original application filed December 26, 1916, Serial No. 138,837. Renewed April 1, 1922. Serial No. 548,793.

To all whom it may concern:

Be it known that I, MARVIN SMITHEY, a citizen of the United States, and a resident of Lawrenceville, in the county of Brunswick and State of Virginia, have invented certain new and useful Improvements in Meters, of which the following is a specification.

My invention relates to improvements in 10 meters of the type in which a plurality of odometers is mounted in a casing, means being provided to drive the odometers simultaneously, certain of the odometers being movable into reading position, and other of 15 the odometers being fixed in position, and it consists in the combinations, constructions and arrangements herein described and claimed.

An object of my invention is to provide 20 a meter of the type described, in which the odometers are mounted so as to move in a plane about a central axis.

A further object of my invention is to provide means for disconnecting the driving 25 means from the common odometer drive and for subsequently disconnecting any one of the odometers, and for resetting it at will.

Other objects and advantages will appear 30 in the following specification, and the novel features of the invention will be particularly pointed out in the appended claims.

My invention is illustrated in the accompanying drawing forming a part of this application, in which:

35 Figure 1 is a plan view of the device.

Figure 2 is a section on the line 2—2 of Fig. 3.

Figure 3 is a sectional view along the line 3—3 of Fig. 2.

40 Figure 4 is a section along the line 4—4 of Fig. 2.

Figure 5 is a section along the line 5—5 of Fig. 2.

45 Figure 6 is an enlarged detail section substantially along the line 6—6 of Fig. 3, certain parts being shown in elevation for the sake of clearness.

Figure 7 is a section along the line 7—7 of Fig. 6.

50 Figure 8 is a section through a portion of the resetting mechanism for the stationary odometers.

Figure 9 is a section along the line 9—9 of Fig. 4.

55 Figure 10 is a perspective view of a portion of the driving mechanism, and

Figure 11 is a sectional view through a portion of the disconnecting mechanism of the movable odometers.

In carrying out my invention I provide 60 a casing 1, (see Fig. 2) which is of cylindrical shape, closed at its bottom, and being provided with an enlarged portion 1^x, which leaves a shoulder 2. Carried by the shoulder is a washer 3 which supports a ring 4. 65 The latter is connected by means of upwardly extending plates 5 (see Fig. 3), with a movable rim 6 in the shape of a ring. This rim is slotted to receive the upper end of the portion 1^x so as to rotate thereon. 70 The rim 6 is provided with an overlapping portion having screws 7 bearing rollers 8, arranged to engage underneath a flange portion at the top of the casing section 1^x, so as to hold the rim 6 in place. The rim 6 75 has secured to it on the under side, a ring 9, this ring supporting in turn a glass plate 10.

On the interior of the casing 1 is a frame having a base portion 11 and uprights 12. As will be seen from Fig. 5, the uprights 12 are extended as shown at 12^x to support a dial plate 13 which is stationary, and over which a needle or arm 14 is arranged to swing. The dial is provided with a scale 15 indicating miles per hour. The plate 13 80 is provided with openings 16 through which the numbers of certain of the odometers may be viewed, as will be explained later.

Journalized in the casing 1 is a drive shaft 17 which is arranged to be connected with the moving parts of a vehicle, not shown. This drive shaft is provided with a worm 18 arranged to engage a gear 19 on a shaft 20, (see Figs. 2 and 10). The shaft 20 bears a worm 21 arranged to engage a gear 22 on a shaft 23, bearing a worm 24, the latter engaging the gear 25 on a shaft 26. It will be noted from Fig. 10 that the shaft 26 is supported in a bearing 27 which is pivotally mounted at 28 on the shaft 23, so that the 95 shaft 26 may be moved around the axis of the shaft 23 as a pivot, while the gears 24 and 25 will remain in mesh.

The shaft 26 is provided with a worm gear 29 which is arranged to engage a worm 105 wheel 30 formed at one edge of a ring 31. This ring consists of two sections which are secured together by means of screws 32 (see Fig. 5), so as to embrace a portion of the ring 4, the ring 31 being rotatable upon the ring 4 as a bearing. The ring 31 is provided with an external gear 33, and has an ex-

tension which is provided with an internal gear 34. It will thus be seen that the ring 31 may be driven by the mechanism which is shown in Fig. 10. The means by which the ring 31, with its gears 33 and 34 drive the odometers, will be hereinafter set forth.

Referring now to Figs. 5 and 6 it will be seen that the frame member 12 supports a plate 35, and that between the plate 35 and the dial plate 13 is mounted a series of shafts bearing disks. Thus in Fig. 6, the shafts 36^a, 36^b, 36^c and 36^d bear the corresponding disks 37^a, 37^b, 37^c and 37^d. The shafts are mounted for revolution about their axes, the disks being numbered as shown in Fig. 3, and the revolution of the disks causing the numbers to appear before the reading opening 16 (see Fig. 1). It will be observed that the shaft 36^a has a single tooth 38^a which is arranged to engage a star wheel or a gear 39^b on the shaft 36^b. The latter has a single tooth 38^b arranged to engage the star wheel 39^c on the shaft 36^c. Similarly this shaft 36^c has a tooth 38^c arranged to engage a star wheel 39^d on the shaft 36^d.

The disk 37^a is a units disk, or the disk of the lowest denomination. It will be observed that its shaft 36^a extends through the plate 35 and is provided with a gear 40 arranged to mesh with an idler 41, which in turn is in mesh with a gear 42, (see Figs. 6 and 7) carried by the plate 35, the latter being in engagement with the internal gear 34 carried on the ring 31. From the construction described above it is evident that when the ring 31 is revolved by means of the mechanism heretofore described, motion is transmitted to the stationary odometer by means of the gears 34, 42, 41 and 40.

The odometer just described is a trip odometer, the total mileage odometer being similar in construction except that instead of having an idler such as that shown at 41 between the gears 42 and 40, its gear 40* which corresponds to the gear 40 of the trip odometer, is directly in mesh with the internal gear 34 (see Fig. 3). The purpose of the idler 41 is to provide a means for disconnecting and resetting the trip odometer. To this end the gear 41 is mounted on a shaft 43 which is mounted so as to rotate about its axis, and also to slide longitudinally with respect to its axis in the plate 35 at one end, and in a guide plate 44 at the other. The shaft 43 is provided with a cone 45 which is arranged to be engaged by the cam portion 46 at the center of a bevel gear 47 which is mounted on a shaft 48 supported in a bearing 49 and being normally acted on by a spring 50. The shaft 48 passes through the casing wall 1 and is provided with a thumb wheel 51 by means of which the shaft may be rotated and also moved toward and away from the

shaft 43. The latter bears a bevel gear 52 arranged to engage the bevel gear 47, while a spring 53 is disposed between the gear 52 and the upper portion of the plate 44.

It will be noted that when the thumb wheel 51 is pushed inwardly, the cam portion 46 will engage the cone 45, pushing the shaft 43 upwardly and carrying the idler 41 clear of the gear 42, the idler still being in mesh with the gear 40. At the same time the gear 52 is brought into mesh with the gear 47 so that on turning the wheel 51, the wheel 40 may be rotated, thereby resetting the odometer. On the release of the thumb wheel 51 the springs 50 and 53 will restore the apparatus to normal, thereby connecting the gears 40 and 42 through the medium of the gear 41.

Referring now particularly to Figs. 2, 3 and 6, it will be seen that the annular member 4 bears a series of uprights 54 at the top of which is secured a ring 55. Between this ring and the member 4 is mounted a series of shafts, like that shown in dotted lines at 56 (see Fig. 9), each shaft bearing a disk 57 and a gear wheel 58. This gear wheel is arranged to slide on the shaft 56 (see Fig. 11), the sleeve of the gear bearing a detent 59 arranged to enter notches 60 in the shaft. The lower end of the shaft 56 is provided with a gear 61. In the present instance, I have shown six sets of these shafts 56 having gears 58. The disks 57 on the shafts 56 are the unit disks of the series of odometers, as shown in Fig. 3. Each set of odometers carried by the ring 55 is driven through the medium of a gear 58, certain of these gears being shown in dotted lines in Figs. 3 and 9, and in full lines in Fig. 2.

The gears 58 are in engagement with the external gear 33 of the ring 31 so that when the ring 31 is rotated, the gears 58, and hence the odometers which are associated with the respective gears 58, will be driven simultaneously. The means by which the remaining disks of any odometer are driven, is the same as that already set forth in connection with the stationary odometers, in Fig. 6, to wit, a mutilated gear and a star wheel, or gear arranged to be engaged by the mutilated gear.

The means for permitting any of the odometers which are carried by the ring 55 to be brought into reading position, is best set forth in Figs. 4 and 10. In these figures, it will be observed that the shaft 26 which bears the worm gear 29, may be swung about the shaft 28 as a pivot, thereby disengaging the worm 29 from the gear 30 which is carried by the ring 31. The end of the shaft 26 projects through a slot 62 in the casing 1. An arm 63 is normally held by the spring 64 against the shaft. This arm is provided with a shoe 65 which

exerts pressure on the shaft 26, but which permits the shaft to turn. A locking lug 66 is secured to the arm 63 so that when the shaft 26 is moved in the direction shown 5 by the arrow in Fig. 4, the locking member 66 is withdrawn from one of the sockets 67 which are carried by the ring or annular plate 4, there being one of these sockets for each of the movable odometers. Now, if 10 the rim 6 is grasped and rotated, it will carry around with it the ring or annular plate 4, the ring 55, and the movable odometers, so that any of these odometers corresponding to the legends on the rim may 15 be moved into reading position. When the shaft 26 is released, the spring will take the worm wheel 29 back into engagement with the gear 30, while the locking lug 66 will enter one of these sockets 67, thereby locking 20 the ring 4 in position, and hence preventing the rotation of the ring due to the driving of the odometers in the manner already described.

The gears 61 are all arranged to engage 25 a large gear 68 on the end of a shaft 69 which is provided with a head 70 which is milled so that it may be easily turned. The engagement of the gears 61 by this gear 68 will occur when the odometer train thus 30 engaged, is in position at the reading openings. In order to shift the shaft 56 I provide any suitable means, such as the forked lever 71.

Mounted on the drive shaft 17 is the centrifugal member 72 which is connected by 35 a link 73^a with a collar 73, the latter being acted upon by a spring 75. The collar bears an arm 76 which is slotted to receive a pin 77 (see Fig. 4), on an arm 78 bearing a 40 segmental gear 79 arranged to engage a gear 80 on the stem 81, bearing a pointer 82 which is arranged to swing over the speedometer dial plate.

From the foregoing description it will be 45 seen that any of the odometers in the outer

ring may be brought at will into reading position, may be disconnected and held in disconnected position, and may be reset.

I claim:

1. In a meter comprising a plurality of 50 odometers actuated from a common source a rotatable support, a group of odometers arranged in a circular series on said support and shiftable by the rotation thereof in succession to reading position, and an 55 odometer situated within such circular series and lying in substantially the same plane as that of the series of odometers.

2. A meter comprising a rotatable support, a group of odometers arranged in a 60 circular series on said support and shiftable by the rotation thereof in succession to reading position, and an odometer situated within such circular series and lying in substantially the same plane as that of the series 65 of odometers, and a common driving means for all said odometers comprising a rotatable ring and gearing between the same and each odometer.

3. In a meter for vehicles comprising a 70 plurality of odometers actuated from a common source a casing having a dial provided with a plurality of reading openings, a stationary odometer adapted to be read through certain of said openings, a support rotatable 75 about said stationary odometer parallel to the face of the dial, and a plurality of sets of odometers carried by said rotatable support and adapted to be brought to a given position to be read through other openings. 80

4. In a meter comprising odometers actuated from a common source, a rotatable support, a group of odometers arranged in a circular series on said support, and shiftable by the rotation thereof to display position 85 in succession, said odometers lying in substantially the same plane such plane being perpendicular to the axes of rotation of the support.

MARVIN SMITHEY.
